(57) **CLAIM**

We claim the ornamental design for a simulated companion, as shown.

DESCRIPTION

FIG. 1 is a front perspective view of a simulated companion according to an embodiment of the invention.

FIG. 2 is a front elevation view of a simulated companion according to the embodiment of FIG. 1.

FIG. 3 is a rear elevation view of a simulated companion according to the embodiment of FIG. 1.

FIG. 4 is a left-side elevation view of a simulated companion according to the embodiment of FIG. 1.

FIG. 5 is a right-side elevation view of a simulated companion according to the embodiment of FIG. 1.

FIG. 6 is a top view of a simulated companion according to the embodiment of FIG. 1; and,

FIG. 7 is a bottom view of a simulated companion according to the embodiment of FIG. 1.
